BROOM MACHINE

Edmund McCaffray, Baltimore, and Charles E. Oyler, Halethorpe, Md., assignors to Edmund McCaffray and B. M. McCaffray, trading as The Baltimore Broom Machine Company, Baltimore, Md.

Application November 14, 1939, Serial No. 304,400

1 Claim. (Cl. 112—6)

This invention relates to broom sewing machines or the like, and more particularly to a device of this character which is provided with a work carrier adapted to receive a broom at an initial idle position and to be shifted to an operative position in proximity to the sewing apparatus.

The general object of the invention is to provide a novel and improved device for facilitating the shifting of the work carrier.

In machines widely in use at the present time, the main frame of the apparatus encloses a space within which the broom to be sewed is adapted to move, and suitable stitching mechanism is provided upon either side of this space to bind the broom straw firmly together as the broom is fed past this mechanism by a gradual movement of the carrier. The carrier in such a machine is pivotally mounted upon a lower or intermediate portion of the main frame and includes a vise for firmly clamping the partly completed broom during the sewing operation. In its initial idle position the vise projects outwardly from the general confines of the main frame and clear of the needles, loopers, and other parts of the stitching mechanism; and after the broom is clamped in the vise, the carrier is grasped by hand at any convenient portion thereof and shoved by main force into position between the stitching devices for effecting the sewing operation.

In these machines, means are usually provided for starting the power operated sewing mechanism automatically upon throwing in the vise, and at the same time initiating the gradual feed of the carrier outwardly during the sewing operation. Means are also generally provided for automatically springing the jaws of the vise open at the end of the outward feed of the carrier after the stitching has been completed.

The present invention contemplates the provision of foot operated means for throwing in the work carrier or vise; and in its preferred embodiment a foot lever is culcrumed upon a stationary part of the main frame, preferably at a point below the horizontal pivot of the carrier, and is operatively connected with the carrier or one of its trunnions by means of a chain and grooved pulley segment, whereby upon applying pressure to the lever, the carrier frame and vise will be rocked into starting position.

Other objects and features of novelty will be apparent from the following specification when read in connection with the accompanying draw-

ings in which certain embodiments of my invention are illustrated by way of example.

In the drawings;

Figure 1 is a fragmentary view in side elevation of a broom sewing machine embodying the principles of the invention, showing a portion of the main frame and stitching mechanism and the broom carrier pivotally mounted thereon.

Figure 2 is a fragmentary view in front elevation of the upper portion of the work carrier;

Figure 3 is a fragmentary view, partly in vertical section and partly in side elevation, as seen from the opposite side from that of Figure 1;

Figure 4 is a fragmentary sectional view of a detail of the automatic feeding mechanism shown in Figure 3; and

Figure 5 is a fragmentary view in front elevation of the lower portion of the machine.

In the drawings, wherein is more or less diagrammatically illustrated a broom sewing machine incorporating the novel throw-in mechanism forming the subject of the present invention, the main frame of the machine is designated generally by the reference numeral 10, as best seen in Figures 1 and 5. Projecting from the front of the main frame 10 are a pair of brackets 11 which are provided with bearings 12 within which are adapted to rotate the trunnion shafts 13 and 14 which serve to pivotally support the work carrier—designated generally by the numeral 15—with respect to the frame. Both of the trunnion shafts 13 and 14 are rigidly received within the cylindrical bosses 17 and 18 of the frame of the work carrier 15.

The work carrier 15 comprises essentially the vise jaws 20 and 21 between which a broom is adapted to be gripped for stitching. The carrier assembly also includes numerous other elements 40 pertaining to the operation of the jaws, the vertical adjustment of the work, and certain other mechanism, only a portion of which is necessary to an understanding of the present invention, and thus only such portions will be described in 45 the present specification.

Before entering into a description of the mechanism comprised in the carrier, the general movements of the carrier will be explained. The carrier is shown in full lines in Figures 1 and 3 50 of the drawings in an intermediate position in which the sewing operation has progressed about half way. Secured to the main frame 10 as by means of a bracket 23 is a portion of the sewing mechanism indicated diagrammatically at 25. A corresponding oppositely disposed sewing de-

vice 25' is shown in Figure 3, and it is obvious that the carrier with a broom clamped in its vise is adapted to move between the sewing mechanisms 25 and 25' during the operation of the machine. Each of the sewing assemblies are of conventional construction and may include thread loopers 26 and 26', through which hooked needles (not shown) are adapted to move in order to transfer the thread through the broom from one side to the other to form the binding stitches.

The initial idle position of the carrier 15 in which it projects outwardly of the sewing mechanism, in readiness to receive a broom, is indicated by dotted lines and is designated by the reference character A. The center line of the mechanism, while in this position, is shown at a and of course passes through the axis of the trunnion shafts 13 and 14. The position in which the carrier is disposed when it is thrown in to start the sewing operation is indicated by the broken lines at B, and the center line of the device when in this position is shown at b. The intermediate position shown in solid lines may be conveniently designated C.

The movement of the carrier from the position designated B to position A is effected gradually or in a step-by-step manner while the broom is being sewed, and the throwing in of the device from position A to position B is effected by novel means which will now be described. Rigidly secured to one of the trunnions—the one designated 14 in the embodiment shown in Figure 5—is a sleeve 28 which carries a pulley segment 30, the segment being grooved as at 31 and having secured at one end thereof as at 32 a chain or other flexible arrangement 33. The upper portion of the chain 33 lies in the groove 31 and its lower end is secured to a link 34 pivotally connected to a foot lever or pedal 35, as at 36. The pedal 35 is pivotally mounted as at 37 to a bracket 38 secured to the lower portion of the main frame 10. It will be readily perceived that upon depressing the pedal 35 the segment 30 will be rocked about the axis of the trunnions in a clockwise direction as viewed in Figure 1. This of course will rock the entire work carrier 15, together with all of its associated mechanism, from position A to position B for initiating the operation of the machine.

From the position indicated at B the carrier is moved during the sewing operation outwardly of the main frame 10 back to position A. For purposes of concise illustration, a device of relatively simple construction for feeding the carrier is shown and described herein, but it is understood that this exemplary embodiment does not represent the most modern and improved construction, and furthermore that any desired practical type of step-by-step feeding mechanism may be employed in the present invention without departing from the scope thereof as defined by the appended claims. Suitably secured to the carrier 15 as by means of a bracket 40 is a bar 42, the remote end of which extends through a depending box-like portion of the main frame designated 43. Extending in parallel relation with the bar 42 and also passing through the box frame 43 is the bar 45, the outer end 46 of which is normally spaced from the abutment 47 carried by the rod 48 which is adjustably secured as at 49 to the upper portion of the bracket 40. The rod 48 is threaded through this bracket portion and is manipulated by the knob 50 and secured in adjusted position as by means of the lock nut 51.

A bell crank lever 54 is fulcrumed as at 55

to a downwardly projecting lug on the bar 42 and has its upper end pivotally connected as at 56 to a projection 57 secured to the bar 45. The other end of the lever 54 is provided with a roller 58 for contact with the rising and falling plate 60, this plate 60 being provided with a cam roller 61 for contacting with an operating cam (not shown), by which it is vertically reciprocated during the operation of the machine. The bell crank lever 54 is biased in a clockwise direction as seen in Figure 3 by means of the spring element 62 secured at its respective ends to a pin 64 on the lever 54 and a pin 65 on the bracket 40.

The right hand end 46 of the bar 45 has a downwardly projecting portion through which a set screw 68 is threaded and adapted to be secured by means of the lock nut 69. The end of the set screw is adapted to abut a projection 70 extending upwardly from the bar 42.

Within the box-like frame portion 43 there are pivoted, above the respective bars 42 and 45, the upper ends of the levers 72 and 75. The lower portions of these levers carry rollers 77 and 78 which are adapted to be intermittently and alternately moved by cams rotated by the main drive of the machine. Each of the bars 42 and 45 within the box 43 is provided with a clamping jaw such as illustrated at 80 in Figure 4. The jaws 80 are periodically clamped upon the respective bars 42 and 45 by pressure of pins or bolts 82 carried by the cam levers 72 and 75.

During the operation of the machine, the bars 42 and 45 are alternately clamped and released. When the bar 45 is released it is drawn by means of the spring 62 against the adjustable stop 47. By adjusting the stop 47 any desired amount of relative movement between the rods 42 and 45 may be attained, and this regulation of the step-by-step movement of the feed will determine the length of the stitches effected by the sewing mechanism during the movement of the work carrier therebetween. Next, when the rod 45 is clamped by the appropriate motion of its cam bar 75, and the bar 42 released by the opposite movement of its lever 72, the work carrier 15 is moved forwardly by means of the vertically oscillating plate or rail 60 which rocks the lever 54 through contact with the roller 58. The adjustable stop 68, 70 prevents excessive movement of the vise during this forward step. This positive gradual step-by-step feed of the work carrier is continued until the carrier reaches the initial position A.

Upon completion of the sewing of a broom, it is removed from the carrier, a new broom inserted, clamped in vise, and the carrier is again thrown into operative position by depression of the treadle 35.

As best seen in Figures 1 and 2 of the drawings, the jaws 20 and 21 are clamped upon the work by means of the following mechanism. Pivoted as at 85 to a relatively stationary portion of the carrier 15, upon either side thereof, are the levers 86. These levers are provided with inwardly turned end portions which are provided with openings through which the horizontal bar 88 extends. At the ends of the levers 86 are pivotally connected the links 89 which are in turn pivotally secured to the jaw 20 as at 90. At other points along the levers 86 upon the opposite side of the fulcrum 85 are pivoted the links 92, which are also pivotally connected as at 93 with the jaw 21. Through suitable connections, including preferably a turnbuckle 95, the rod 96, the offset link 98, and the bell crank

99, the levers 86 are connected for operation to the bifurcated foot lever or treadle 100, which is pivoted on a stationary fulcrum 100' supported by the main frame. The bell crank 99 is fulcrumed as at 101 between and to the arms of the lever 100 and has a downward extension 102 which is pivotally connected to one end of a horizontal lever 104 which is pivoted at an intermediate point 105 to a relatively stationary portion of the carrier 15. The forward end of the lever 104 pivotally carries as at 106 the locking lever 108. This lever is biased in a counter-clockwise direction by means of the spring 109. The lever 108 is provided with a series of teeth 110 which are adapted to be engaged by a dog 112 carried by the treadle 100. The lower end of the lever 108 is provided with the spring pressed dog 115 adapted under certain circumstances to abut the projection 116 carried by a bracket 117 secured to the lower part of the main frame 10. These connections are substantially the same as those shown in the patent to Oyler and Parker 1,071,332 and reference to that patent is made for further disclosure of the details of the machine not directly concerned with the present improvement.

The operation of the vise actuating means will be readily apparent. In order to clamp the jaws 20 and 21 upon a broom the treadle 100 is depressed which, through the elements 99, 98, 96, 95, and 88, will rock the levers 85 in a clockwise direction as seen in Figure 2. This movement, through the links 89 and 92, will move the jaws 20 and 21 toward each other and clamp the broom. Arrangement is made for clamping brooms of differing thicknesses, and thus the downward movement of the treadle 100 will continue until the dog 112 engages the proper tooth 110 on the lever 108, the spring 109 urging the lever 108 toward dog engaging position. After depressing the treadle 100 and properly clamping the broom, the pedal 35 is actuated in order to throw the entire work carrier device 15 into operative position.

The vise jaws 20 and 21 are adapted to be automatically opened upon completion of the sewing operation by the contact of the dog 115 with the abutment 116, whereupon the lever 108 is rocked in a clockwise direction and the tooth 110 is released from the dog 112. A spring 120 connected between a pin 121 on one of the vise jaws and a point 122 on the foot lever 100 exerts a lifting force on the lever and, when the latching lever 108 is released, the foot lever is raised and the vise is opened.

Various changes and modifications may be made in the embodiments illustrated and described herein without departing from the scope of the invention as defined by the following claim.

Having thus described the invention, what is claimed as new and desired to be secured by Letters Patent is:

In a broom sewing machine of the class described, in combination, a main frame, sewing mechanism thereon, a broom carrier frame provided with trunnions supported in fixed bearings carried by said main frame for limited swinging movement from an initial idle position for the insertion of a broom to be sewed, to an operative position with respect to said sewing mechanism, from which latter position the carrier frame may be fed back to the initial position during the sewing operation, means for swinging said carrier frame from said initial idle position to said operative position comprising a pedal fulcrumed on said frame at a point below the trunnion mounting of said carrier, a peripherally grooved pulley segment fixed upon one of the trunnions of said carrier, a chain secured to said segment, trained through said groove, and connected with said pedal, whereby the depression of said pedal causes the trunnion to rock and the carrier frame to swing into operative position.

EDMUND McCAFFRAY.
CHARLES E. OYLER.
